MOTOR DRIVEN LAMP UNIT AND METHOD
 Edward C. Sawyer, 9200 River Valley, Brighton, Mich.
 Filed Mar. 21, 1960, Ser. No. 16,273
 2 Claims. (Cl. 240—49)

This invention relates to a motor driven lamp unit and refers more particularly to a lamp unit which is particularly adapted to illuminate a large area.

In order to illuminate a large area, it has been necessary in the past to employ several individual light units carefully arranged to cover the entire area with some degree of uniformity. At best it is possible only to approach a condition in which the area is lighted with uniformity, and invariably a large number of lamps are required to do the job. This involves a substantial expenditure of money both in equipment and in electric power to operate the lamps.

One object of this invention is to provide a single power operated lamp unit which is particularly adapted to illuminate an area much larger than heretofore has been considered possible.

Another object of the invention is to provide a lamp unit having means for moving the lamp in cycles through a fixed path at a high rate of speed such that the elapsed time per cycle is on the order of the light retention time of the normal human eye or less. As a result, the entire area embraced by the fixed path will be flooded with light, and although the illumination of any part of the path is intermittent, the speed of the lamp is so fast that there is no flicker or interruption in illumination apparent to the eye.

Still another object of the invention is to provide a lamp unit as described above having a support provided therefore mounted for rotation, means for mounting the lamp unit on the support for pivotal movement about an axis at right angles to and intersecting the axis of rotation of the support, means for locking the lamp unit in selected positions of pivotal adjustment, and means for rotating the support and lamp unit as described above to illuminate the large area covered by the rotating lamp unit.

A still further object of the invention is to provide a lamp unit as described above in which the center of gravity of the lamp unit lies on the intersection of the axis of rotation of the support and the axis for pivotal adjustment of the lamp unit, so that the lamp unit is perfectly balanced and will not set up vibrations in the apparatus during operation.

Another object of the invention is to provide a lamp unit as described above having a hollow shell completely enclosing and rotating with the lamp unit, the outer surface of which is symmetrical with respect to the axis of rotation of the lamp unit and its support.

Other objects and features of the invention will become apparent as the description proceeds, especially when taken in conjunction with the accompanying drawings, wherein:

FIGURE 1 is a side elevational view of a motor driven lamp unit, with the hollow shell in section, constructed in accordance with my invention.

FIGURE 2 is a view looking down on the structure of FIGURE 1 with the hollow shell in section.

Referring now more particularly to the drawing, the lamp unit is generally indicated at 10 and the support at 12. The lamp unit 10 comprises a lamp 14 of the usual construction which can be purchased in any store handling this particular class of goods. The lamp 14 has a casing 16 which is cone shaped and closed at the front by a glass window 18, and the electrical terminals for energizing the filaments of the lamp within the housing are at the small end of the lamp opposite the glass 18.

The support 12 is in the form of a yoke having the

2

spaced upwardly extending arms 20 and 22. The lamp unit 10 is supported by the arms of the yoke for pivotal adjustment in a manner more fully described hereinafter. The lower end of the yoke is formed with a depending extension 24 which is coupled to the hollow drive shaft 26 of motor 27 by a collar 28. As seen in FIGURE 1, the extension 24 and drive shaft 26 extend into opposite ends of the collar and are releasably secured thereto by set screws 30.

10 The motor 27 is mounted with the axis of its shaft 26 vertical. The drive shaft 26 as well as the supporting yoke 30 are preferably disposed vertically for rotation about their aligned axes generally indicated at 42.

15 The lamp unit includes a generally U-shaped mounting bracket 44, the legs of which are secured at their ends, as by welding, to the large end of the lamp casing 16, and the portion connecting the legs of the bracket extends across the small end of the lamp and is secured thereto. A ring 46 encircles the lamp near its midpoint, and the legs of the bracket 44 have intermediate opposed parallel portions 48 which are permanently secured to diagrammatically opposite sides of the ring 46. The legs 20 and 22 are formed with aligned apertures which register with apertures in the ring 46 and in the parallel portions 48 of the bracket legs, and pivot studs 52 extend through the aligned apertures. The pivot studs are aligned and define the axis for pivotal adjustment of the lamp unit with respect to the supporting yoke. The axis of pivotal adjustment is indicated by the reference numeral 54 and extends at right angles to and intersects the axis of rotation 42 of the support. The pivot studs 52 are each in the form of a bolt having a head on one end and threaded on the other to receive a wing nut 56. By tightening the wing nuts, the lamp unit may be locked in selected positions of pivotal adjustment with respect to the axis 54. If desired, the engaging surfaces of the supporting yoke leg 22 and the parallel portion of the bracket 44 may be serrated, that is formed with engaging radial serrations, to provide a more positive locking action when the wing nuts are tightened.

30 Because of the high rate at which the support 12 and lamp unit 10 are rotated, near perfect balance is required so that no vibration is set up. It will be noted that the supporting yoke 12 is symmetrical with respect to the axis of rotation 42. Moreover, the center of gravity of the lamp unit 10, including the lamp 14 and its component parts, the bracket 44 and ring 46, lies on the intersection between the axis of rotation 42 and the axis of pivotal adjustment 54. Also, the pivot studs and wing nuts are 35 identical and in perfect balance, being equal distances to the axis of rotation.

35 The lamp unit and the portion of the support above the depending extension 24 is completely enclosed within a hollow shell sphere 60 made of glass or other transparent material. Actually the shell need be transparent only in the front section to transmit the beam of light from the lamp. The sphere is made up of two half sections, the circular marginal portion of one of which being displaced radially inwardly as shown at 62 to provide a surface to surface engagement with the marginal portion 45 of the other. The sections of the sphere may be press fitted together to provide a joint sufficiently tight to withstand the stress during rotation, or if desired, a small amount of adhesive may be employed to secure the joint. The lower portion of the sphere is provided with an aperture to clear the collar 28 and such lower portion is flattened in a circular area as shown at 66 to lie flat against the radial enlargement on the yoke. Fasteners 68 may be provided for removably securing the flattened portion of the sphere sections to the radially enlarged portion of the support. The shell is of course symmetrical with respect to axis 42. The main purpose of the shell

is to cut down on air resistance, which is an important factor at the speeds involved. The shell rotates with the lamp and is such that air friction and hence power consumption are reduced. Also, there is little or no tendency for whistling noises to develop during rotation.

Normally the apparatus will be set up at a high support over the area to be illuminated with the axis of rotation 42 disposed vertically. The lamp 18 may then be adjusted pivotally with respect to the axis of rotation 54, and then locked in selected position by the wing nuts 56. Thereupon the sections of the sphere are assembled in position and secured to the support to rotate as a unit therewith. The motor 40 is then operated to drive the shaft 26 and lamp unit at a high rate of speed. The lamp unit is rotated at a speed such that the elapsed time per revolution is equal to the light retention time of the normal human eye or less. The object is to avoid any apparent flicker to the eye in the area illuminated. The lamp will light up the entire area within its sweep and the lighted area will appear to be continuously illuminated although in fact any segment of the area is illuminated only intermittently. However, the speed of the traveling beam of light is such that a light image is retained by the eye between cycles so that the eye is not aware of any intervening dark periods. The normal human eye will not distinguish any flicker in an intermittent light source which flashes 30 or 40 times a second. In fact, it is said that the eye will retain an image for a tenth of a second so that actually the device might be operated at a speed as low as 10 revolutions per second. However, at this speed there is some chance for flicker and therefore a higher speed, on the order of 30 to 40 revolutions per second, is recommended. Hence, the unit 10 should be rotated between 1800 and 2400 revolutions per minute. This is independent of the angle of adjustment of the lamp unit with respect to the axis 54. While the speed may vary, it should be such that the time required for one revolution is on the order of the light retention time of the normal human eye or less.

It will be noted that the drive shaft 26 and support 12 are provided with passages 70 and 72 for electric wiring 74 to the lamp unit. If the wiring should produce an out-of-balance condition, this can be compensated by counter-balancing the yoke.

The angle of the lamp unit with respect to the axis 54 may be adjusted by removing the enclosing shell 60. This can be accomplished readily by unscrewing the fasteners 68 and applying sufficient force to release the press fitted marginal connection between the sections of the sphere.

What I claim as my invention is:

1. Apparatus for illuminating an area, comprising a single lamp unit adapted to emit a single beam of light when energized, a support for said lamp unit, means 5 mounting said support for rotation about a fixed axis through the center of gravity of said support so that said support is in perfect dynamic balance when rotated, means mounting said lamp unit on said support for rotation as a unit therewith and for pivotal movement about a pivot axis at right angles to and intersecting the axis of rotation of said support, said second-mentioned means including spaced, aligned trunnions lying on said pivot axis and respectively located on opposite sides of said lamp unit, means for locking said lamp unit in selected positions of pivotal adjustment, and means for rotating said support continuously at a high rate of speed such that the elapsed time per revolution is on the order of the light retention time of the normal human eye or less, the center of gravity of said lamp unit lying on the intersection of the axis of rotation of said support and said pivot axis so that said lamp unit is in perfect dynamic balance when rotated, said trunnions being spaced equal distances from said intersection of said axes, and a spherical shell having a smooth outer surface completely enclosing and secured 25 to said support for rotation as a unit therewith, the center of gravity of said shell lying on the axis of rotation of said support, said shell being circular in all sections taken at right angles to the axis of rotation and being symmetrical with respect to said axis of rotation, said shell being transparent at least in the region aligned with the beam of light from said lamp unit, said shell being composed of two half-sections removably secured together along their margins, and the plane of said margins containing said axis of rotation.
2. Apparatus for illuminating an area as defined in claim 1, wherein said support is in the form of a yoke having legs on opposite sides of said axis of rotation spaced equal distances therefrom, said legs straddle said lamp unit, and said trunnions are respectively carried by 40 said legs.
